UNITED STATES PATENT OFFICE.

VALDEMAR E. HANSEN, OF CHICAGO, ILLINOIS.

PICTURE-FRAME CONSTRUCTION.

Application filed June 7, 1926. Serial No. 114,206.

This invention relates to picture frames formed of cardboard, fibre board, or similar light sheet material, as a substitute for heavier and more expensive material, such as wood, metal, etc., the objects of the invention being to provide a frame of this class which may be economically manufactured but still of an attractive appearance.

This improved construction may be made 10 as indicated in the drawing, wherein:

Figure 1 is a rear view of the body part of the frame, formed of laminated strips of cardboard.

Fig. 2 is a sectional detail taken on a line 15 2—2 of Fig. 1.

Fig. 3 is a sectional detail of a completed frame.

Figs. 4, 5 and 6 are sectional details indicating different forms of bevelled facings 20 with which the frame may be provided.

The entire structure is made of cardboard, except for the surfacing or covering on the cardboard part of the frame. The surfacing is made of leather, imitation leather, 25 oiled or parchment paper, fabric, etc. The body of the frame is composed of two sets of cardboard strips, four strips in each set, forming a rectangular frame. The strips 1 of one set are wider than the strips 2 of the 30 remaining set and it may be seen from Fig. 1 that the strips of cardboard 1 meet at their edges 3 and the strips 2 meet at their edges 4. Thus the weak points of each rectangular frame formed by strips 1 and 2 are reinforced, since the two frame structures are 35 glued together at their faces with the seams protected.

Since the set of strips 1 are wider than the set of strips 2 a suitable recess 5 is provided for receiving the glass mat and picture.

The face of the frame is given a bevelled appearance much like that common to many wood picture frames, merely by making use 45 of strips of cardboard 6, mounted upon the cardboard strips 1, as indicated in Figs. 3 to 6 inclusive. The strips of cardboard may

be scored at 7, as indicated in Figs. 4, 5 and 6 to produce various bevels. To produce the structure shown in Fig. 3 strips of cardboard 8 are mounted edgewise along the outer edge of the strips of cardboard 1.

The entire structure is glued together at all meeting edges of the cardboard forming the same, but is strengthened and given the 55 desired appearance by a surfacing 9 of leather, or other suitable surfacing material.

The leather 9 is wrapped around the frame, as indicated in Fig. 3 and glued thereto.

A picture frame constructed as above indicated is, of course, of light weight, but of ample strength for the ordinary purposes of picture frames and may be highly attractive, dependent upon the nature of the covering material 9.

I claim:

A picture frame comprising a plurality of pairs of strips joined at their ends to form a polygonal frame and having each side 70 member composed of back and front rectangular strips of cardboard glued together face to face, said front strips being wider than said back strips, the outer side edges of said strips being in registry so as to 75 form a recess at the inner sides of said edges for a glass, a mat, and a picture, one strip of each pair being as much shorter than the other strip as the width of the adjacent corresponding strips, said side members being joined by overlapping and gluing together the protruding ends of opposite strips so that the end edges of the shorter strips abut against the side edges of the adjacent longer strips, a beveled facing of 80 cardboard on said front strips for imparting rigidity thereto, and a flexible covering material surrounding said frame members and glued thereto for holding said beveled front and back strips securely together.

Signed at Chicago this 4th day of June 1926.

VALDEMAR E. HANSEN.
